JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

STOP MECHANISM.

1,184,961.

Specification of Letters Patent.

Patented May 30, 1916.

Application filed June 13, 1914. Serial No. 844,896.

To all whom it may concern:

Be it known that I, JOHN KIEWICZ, a citizen of the United States, residing at Hyde Park, in the county of Suffolk and State of Massachusetts, have invented certain new and useful Improvements in Stop Mechanisms, of which the following is a specification, reference being had therein to the accompanying drawing.

10 This invention relates to stop mechanisms and more particularly to a mechanical contrivance associated with the driving mechanisms of machines of various sorts for effecting the stoppage thereof in a desirable manner.

An object hereof is to afford an efficient and durable stop mechanism adapted to employment with light, fast-rotating machines such as sewing machines, power 20 driven from a continuously rotating shaft.

Another object is to provide a stop mechanism which is easily controlled and operated and serves to promptly, yet without shock, bring the main shaft of the machine 25 to rest preferably with the needles or other operating parts of the machine at a predetermined point in the cycle of their operations.

Other objects hereof will be perceived 30 from the hereinafter following description of an illustrative mechanism embodying the principles of this invention.

To the attainment of the objects referred 35 to the present invention consists in the novel combinations, arrangements, mechanisms, devices, details and other features illustrated or described herein.

Figure 1 is a front elevation of a portion 40 of a sewing machine embodying a stop mechanism constructed on the principles of this invention, the front side being broken away to disclose the interior. Fig. 2 is a right elevation thereof. Fig. 3 is a section on the plane 3—3 of Fig. 1. Fig. 4 is a section 45 on the plane 4—4 of Fig. 1. Fig. 5 is a section on the plane 5—5 of Fig. 4.

The same reference numerals designate 50 corresponding parts in the several views of the drawings.

For convenience of illustration, the general type of sewing machine illustrated in prior Patent No. 1,047,537 of December 17th, 1912, has been selected and such prior patent may be referred to for the general operation 55 of such a machine and for various

details not constituting *per se* the present invention.

The hollow base 9 of the machine supports the stitching mechanism, which would be at the left end of the machine and for convenience is omitted, and the driving and stop mechanism which is at the right end, partly within and partly without the base. The main shaft 10 extends from the driving mechanism to the stitching mechanism and operates the needles and coöperating parts.

A presser-foot 11 is shown carried at the forward end of the arm 12 of a swinging lever the shaft 13 of which affords a pivotal bearing and also carries a second or actuating arm 14 extending within the base 9. The arm 14 has at its extremity an extension 15 to permit the lifting of the presser-foot, against spring 16, by a lifting part or swinging arm 17, which is held up by spring 18 so that its stud 19 bears on a device or cam 20 on main shaft 10 as shown. Thereby the presser-foot is raised automatically when the machine is stopped. When the machine is started the arm 17 is shifted to the left, so that cam 20 will not lift the presser-foot, by means later described.

The main shaft is supported in bearings, one of which, 21, is shown, and the shaft extends from the interior of the base through its right hand wall to the exterior parts.

Referring now more particularly to the driving and stop mechanism, it involves a brake device associated with the rotary shaft 10 or preferably with a hollow drum 25 secured upon the shaft, and with contacts or lugs upon the shaft and the brake device respectively, the same being adjustable relatively endwise, that is to say longitudinally of the main shaft. The brake device preferably comprises a brake shoe located in the interior of the drum and in the form of an arc of a circle, and the contact for operating the brake shoe is movable endwise in such manner that the contact is brought into line with the contact that rotates with the shaft, so that the braking force is applied by the momentum of the machine to effect the stoppage. The contact which is carried by the shaft or drum is yielding so as to prevent undue shock and to secure the application of the braking force in a progressive manner. With the described parts is combined a power uncoupler in the nature of a belt shifter which may shift a belt

- to a loose pulley. A single means or control part serves in one operation for uncoupling the power and adjusting the brake device so that the lugs coöperate to bring 5 about a prompt yet comparatively easy and shockless stoppage in which invariably the stitching mechanism or other parts of the machine will be brought to rest in a predetermined position or point.
- 10 At the right extremity of the main shaft 10 is a hand wheel 22. Near the hand wheel is a loose belt pulley 23 adjacent to a fast belt pulley 24, which, for convenience, may be formed in one part with a drum 25 secured upon it, so as to rotate with the main shaft. A belt shifter 28 serves to couple or uncouple power from the main shaft, this being mounted at the end of a sliding rod 29 which is continuously pressed toward the 15 right by spring 30, tending to normally hold the belt on the loose pulley. The spring 30 surrounds the second slide rod 41 pressing against a yoke on the latter so as to move both slide rods to the right, the two rods being connected by a swinging arm 32 projecting downwardly from a cross shaft 33 which, at the front of the machine, has a second arm 34 provided with a handle 35 or a treadle rod 36, or both. By now 20 depressing the treadle rod or handle the arm 32 is swung to the left and the belt is shifted to the fast pulley, the release of the handle or treadle again restoring the belt to the loose pulley.
- 25 Coöoperating with the interior surface of the drum 25 is a brake device which will now be described. This device includes a member or pin 39, which is shiftable endwise between its inoperative position to the left and its operative position to the right, in which latter position it effects the braking of the drum and shaft. The pin 39 is carried in its endwise movements by a yoke 40 rigidly secured to the slide rod 41, the 30 latter being adapted to oscillate slightly to permit swinging of the yoke and pin for a purpose that will be later described.
- 35 It is proposed to move the slide 41 with or by the movement of the slide 29 which carries the belt shifter. Instead of rigidly connecting them it is preferred to employ the arm 32 for actuating them both; thus a stud 42 projects rearwardly from the arm 32 into a side recess in the slide rod 41. 35 Thereby the brake pin 39 and the belt shifter may be moved to the right or to the left in unison, and the belt shifter is given a greater extent of movement than the brake pin. In effect the arm 32 and the parts 40 which serve to move it constitute a single means for both uncoupling the power and shifting the brake pin endwise into operative position and vice versa.

The brake device comprises, as already 45 stated, an interior brake shoe 43. This is

shown substantially in the form of a half ring, and one end of it is pivoted by a short fulcrum shaft 44 to the frame of the machine in such position that the half ring lies within the hollow of the drum in rubbing contact therewith. 70

In all of the figures the parts are shown in their position when the machine is stopped.

The fulcrum shaft 44 of the brake shoe 75 permits the latter to be slightly swung so that it can be pressed into more or less intimate frictional engagement with the drum interior surface.

It will be understood that in the normal 80 running of the machine the pin 39 rests over the free end of the shoe 43, but is held in its leftward or inoperative position. After the controlling treadle has been released, the spring 30 tends to move the 85 slide rods to the right, but they are restrained until the proper point in the rotation of the shaft 10 by the fact that the arm 17 on the slide rod 41 has its stud 19 blocked by the extension 50 of the cam 20. 90 When the extension 50 has passed the stud 19, the slide rods move to the right and the stopping action commences.

When the parts have sprung to the right, as described, a cam 45 on the main shaft 95 10 comes into play to depress the yoke 40 by means of a contact screw carried by the latter, as best seen in Fig. 2. The depression of the yoke forces downwardly the pin 39, carried by the yoke, and, as seen 100 in Fig. 4, this causes the brake band 43 to press against the drum, giving a sort of initial friction which very largely retards the shaft's rotation during a fraction of a revolution. 105

The final retarding and stopping is to be effected by means of a stop 46 carried by and rotating with the drum. This stop is preferably yielding. It is shown of the form having a leftwise projection carried 110 by a radial arm portion, which loosely surrounds the drum hub, and which, to the right of the drum partition, is provided with a coiled spring 47 affording a limited extent of yielding with increasing resistance. It will be understood that the active portion of the stop 46 rotates in a path which intersects the path of the pin 39, so that when the latter has been moved to its operative position for stopping the machine, 115 as shown in Fig. 5, the two are adapted to meet. It will be understood that Fig. 5 is a view seen from the rear and that the terms right and left must be reversely considered on that figure. Fig. 4, which is a 120 left view of the interior parts, shows a clockwise rotation of the drum. It has already been explained that the point of time in which the slide rods and the pin 39 shift to the right is controlled by the cam 20. 125 130

The control is such that the pin may not jump into its operative position until after the rotating stop 46 has passed the position occupied by the pin, so that the shaft 5 is required to make a substantial fraction of a revolution before the stop and pin actually do contact.

After the stopping parts have shifted to the right and after the yoke 40 has been 10 depressed by the cam 45 for applying initial retarding pressure on the brake shoe 43, the shaft rotation continues at rapidly reducing speed until, after a fraction of a revolution, the pin 39 is struck by the stop 46. 15 Before the actual striking, however, the pin 39 has been passed by a swinging lock 48 controlled by spring 49, the purpose of which is to prevent any substantial rebounding of the shaft after the final 20 stoppage. As soon as the stop 46 strikes the pin 39 the following operations occur: The impact upon the stop finger increases the pressure of the latter upon the brake shoe 43, so as to largely increase the retarding effect upon the rotation of the shaft. 25 Also the strong coiled spring 47 at once commences to yield and compress, thus imposing a quickly increasing pressure upon the stop 46, so that in turn the stop 46, acting through the pin 39, imposes increasing pressure upon the brake shoe. Finally, however, the extent of yielding of the stop 30 46 is limited by the slot in which it plays with the result that at the end of the 35 stopping operation there is a positive rigid stoppage, the brunt of which is taken by the brake shoe, so that at once the already greatly retarded shaft is further restrained and brought positively to a definite stoppage 40 in the position shown in the figures. Any tendency to rebound is checked by the lock 48 striking the pin 39.

It will thus be seen that there has been described a stop mechanism embodying the 45 features and attaining the objects and advantages referred to and further advantages will be apparent to those skilled in the art. Since many matters of arrangement, design, detail and other features may be varied 50 without departing from the principles hereof, no limitation to such features is intended excepting so far as specified in the appended claims.

What is claimed is:

55 1. In combination, a rotary shaft, a shaft retarder, a rotating stop carried by the shaft, and a shifting device coöperating with said retarder and stop adapted to be shifted relatively to both said retarder and stop into the path of the stop, whereby the stop may act through the device to apply the retarder, means for at will effecting the shifting of the device to effect stoppage, and 60 automatic means to prevent its shifting at an improper point in the shaft's rotation

and a lock rotating with the shaft coöperating with the device to prevent rebound.

2. In combination, a rotary hollow drum, means to rotate it, a brake shoe at the interior surface of said drum extending over a substantial arc and having one end anchored, 70 a rotating stop carried by and having a limited yielding movement in the drum, and a shifting block or pin coöperating with said brake shoe and stop, located to contact the free end of said brake shoe and adapted to be shifted into the path of the stop, so that when struck thereby it will apply said brake shoe, whereby the shaft is retarded and definitely stopped, means for at will effecting 80 the shifting of the block to effect stoppage, and automatic means to prevent its shifting at an improper point in the shaft's rotation and a lock rotating with the drum coöperating with the block to prevent rebound. 85

3. A stop mechanism for high speed machines including in combination with a rotating shaft, a hollow drum fixed on said shaft, a brake member within the drum adapted to act frictionally against the drum 90 interior surface for retarding the shaft, a rotating stop member carried around with the shaft, a non-rotating stop member located to cause a pushing action on said brake member for applying the brake and adapted 95 to be shifted into the path of said rotating stop member and when struck thereby to transmit the momentum to the brake member for retarding and finally stopping the shaft; and means for shifting said non-rotating stop member into the path of said rotating stop member at suitable times, one of said stop members fitted to yield under increasing resistance to a limited extent, whereby increasing braking action is effected terminated by a final positive stoppage in a definite shaft position, and the energy being dissipated by the brake between the meeting of said stop members and the final stoppage. 100

4. A stop mechanism for high speed machines including in combination with a rotating shaft, a brake member for retarding the shaft, a rotating stop member carried around with the shaft, a non-rotating stop member adapted to be shifted into the path of said rotating stop member and when struck thereby to transmit the momentum to the brake member for retarding and finally stopping the shaft, a device actuatable at suitable times for causing the shifting of said rotating stop, a guard rotating with the shaft for restraining such shifting until the rotating stop is at a point substantially in advance of the non-rotating stop, and automatic means controlled by the shaft for applying an initial retarding effect in the period between the actuation of said device and the impact of said stop members. 115

5. A stop mechanism for high speed ma- 120

- chines including in combination with a rotating shaft, a hollow drum fixed on said shaft, a rigid, non-rotating, arc-shaped brake shoe located within the drum adapted to be pressed against the drum interior surface for retarding the shaft, a rotating stop projection located within the drum and a non-rotating stop member adapted at suitable times to be shifted into a position between said rotating stop projection and said brake shoe, one of said members constructed to yield whereby the brake may take effect between the time of impact and the final stoppage.
6. A stop mechanism for high speed machines including in combination with a rotating shaft, a hollow drum fixed on said

shaft, a rigid, non-rotating, arc-shaped brake shoe located within the drum adapted to be pressed against the drum interior surface for retarding the shaft, a rotating stop projection located within the drum and a non-rotating stop member adapted at suitable times to be shifted into a position between said rotating stop projection and said brake shoe, said stop projection being mounted to resiliently yield to a limited extent with relation to said drum. 20 25

In testimony whereof I affix my signature in presence of two witnesses.

JOHN KIEWICZ.
